Patented Apr. 21, 1964

198,025

GAUSSMETER

Richard W. Seabury, Jr., Old Lane, Towaco, N.J., and
William A. Yonkers, 75 Pollard Road, Mountain
Lakes, N.J.

Continuation of design applications Ser. No. 66,615,
Sept. 5, 1961, and 66,616, Sept. 6, 1961. This appli-
cation Dec. 17, 1963, Ser. No. 77,884

Term of patent 14 years

(Cl. D26—1)

Fig-7

Fig. 1

FIGURE 1 is a front isometric view of a gaussmeter showing one form of our new design, wherein the housing is higher than it is wide and there are three adjusting knobs on the front panel and arranged as a series one above another along a vertical, central line;

FIGURE 2 is a similar view but showing the indicating instrument in partially raised position and the pivotally-mounted handle in the reverse position;

FIGURE 3 is a rear elevational view of the gaussmeter shown in FIGURE 1;

FIGURE 4 is a rear isometric view with the indicating instrument shown in partially raised position;

FIGURE 5 is a front isometric view of a gaussmeter showing another form of our design, wherein the housing is wider than it is high and there are two adjusting knobs on the front panel spaced one above the other along a vertical central line and a plurality of additional knobs;

FIGURE 6 is a view similar to FIGURE 5 but showing the indicating instrument in partially raised position and the pivotally-mounted handle in the reverse position;

FIGURE 7 is a rear elevational view of the gaussmeter shown in FIGURE 5; and

FIGURE 8 is a rear isometric view of the gaussmeter shown in FIGURE 5 but with the indicating instrument shown in partially raised position.

We claim:

The ornamental design for a gaussmeter, as shown and described.
